(57) **CLAIM**

The ornamental design for a monitor, as shown and described.

DESCRIPTION

FIG. 1 is a front, right and top perspective view of a monitor, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof;

FIG. 9 is a perspective view of the monitor shown in a folded state;

FIG. 10 is a perspective view of the monitor shown in a state of use;

FIG. 11 is an enlarged detail view of portion '11' of FIG. 1 thereof;

FIG. 12 is an enlarged detail view of portion '12' of FIG. 2 thereof;

FIG. 13 is an enlarged detail view of portion '13' of FIG. 5 thereof; and,

FIG. 14 is an enlarged detail view of portion '14' of FIG. 6. The even-dash broken lines shown in the drawings illustrate portions of the monitor that form no part of the claimed design.

The dot-dash broken lines represent the extents of the detail views and enlargements and form no part of the claimed design.

1 Claim, 14 Drawing Sheets
